UNITED STATES PATENT OFFICE.

WILLIAM C. SCHMIDT, OF RICHMOND, VIRGINIA.

INDICATING-BOTTLE.

No. 891,956.

Specification of Letters Patent.

Patented June 30, 1908.

Application filed July 13, 1905. Serial No. 269,518.

To all whom it may concern:

Be it known that I, WILLIAM C. SCHMIDT, a citizen of the United States, residing at Richmond, in the county of Henrico and State of Virginia, have invented certain new and useful Improvements in Indicating-Bottles; and I do hereby declare the following to be a full, clear, and exact description of the invention, such as will enable others skilled in the art to which it appertains to make and use the same.

My invention relates to new and useful improvements in bottles and particularly to that class known as indicating bottles, the object of my said invention being to produce a bottle stopper which will indicate any attempt to refill the bottle after the original contents thereof have been removed.

In order that my invention may be thoroughly understood, I have illustrated the same in the accompanying drawings, a full and exact description thereof being contained in the annexed specification.

In the drawings, Figure 1 is a front elevation of my improved stopper located in the neck of a bottle, the bottle neck being shown in section. Fig. 2 is an elevation of my improved device indicating that the bottle has been refilled. Fig. 3 is a vertical section through my improved device. Figs. 4 and 5 are plan views of certain parts of my device. Fig. 6 is a perspective view of my device, the several parts thereof being disconnected. Fig. 7 is a view similar to Fig. 3 with the addition of a disk or washer valve. Fig. 8 is a vertical section through a modified form of my device. Fig. 9 is a perspective view of said modification showing the parts thereof disconnected. Fig. 10 is a view similar to Fig. 8, with the addition of a disk or washer valve.

In the several views like letters of reference designate similar parts of my device.

A, in the drawings, designates the bottle provided with the cylindrical mouth a which is provided at its lower end with the annular shoulder a' and groove a^2 . B is a circular disk constructed to snugly fit into said mouth a and rest upon said flange a' , said disk being provided with an annular groove b directly opposite groove a^2 , forming a recess adapted to be filled with cement x to lock said disk in place. C is a hollow cylindrical portion projecting upwardly from said disk, the same being open at its lower end and provided at its upper

end with the threaded orifice c . D is a transparent cup shaped portion or compartment surrounding said cylindrical portion and of sufficiently larger diameter to form the annular groove d . Said cup shaped portion D preferably extends slightly above the cylindrical portion C and is provided with lugs d' adapted to retain the cup shaped portion D in the center of the mouth of the bottle, thus forming a passage for the outflow of the contents which first flows through openings b' in the disk portion B. E is an indicator comprising a ribbon located in the groove d and upon which is printed any suitable word as "Refilled", which word is covered with a non-transparent substance which may be readily dissolved or destroyed as a composition of chalk or a thin layer of gelatin.

F is the stopper constructed to close the mouth of the bottle and the cup shaped compartment D and also to prevent access to said cup shaped compartment D, the washers f and f' respectively being employed to make airtight connections when the bottle is closed. Said stopper is provided with the screw stem f^2 adapted to pass through the orifice c and being prevented from withdrawal therefrom by a locking ring f^3 constructed to fit in the groove f^4 .

f^5 is a cork or other stopper which is employed to close the lower end of the hollow cylinder C after the ring f^3 has been placed upon the stem f^2 .

G is a conical shaped valve located in the conical shaped portion a^3 of the neck of the bottle, said valve permitting the outflow of the contents but preventing refilling.

As shown in Fig. 7, an additional valve may be provided by placing a washer H on top of the disk portion B, which it is obvious will act similarly to the valve G, that is it will permit the outflow of the contents through the openings b' but will close said opening when the liquid is forced into the bottle. If desirable this valve may be made buoyant so as to close the openings b' if an attempt is made to fill the bottle when inverted.

In Figs. 8, 9 and 10, I have shown a slightly modified form of my invention. In this form of construction, instead of the hollow cylinder C, I provide the upright cylindrical portion C' with a recess c' to receive the stem f^2 . This portion C' may be made separate

from the disk portion B as shown or integral therewith and adapted to be secured thereto by any suitable means.

I designates a disk constructed to screw into a circular recess J above the groove d, said disk and the wall of said recess being provided with the corresponding notches i and j respectively, constructed to be filled with cement or a pin to prevent said disk from being unscrewed. Said disk is provided with the openings i² directly over the groove d and with the central threaded orifice i³ through which the stem f² is screwed, the same being prevented from being withdrawn by a locking ring as before described.

In Fig. 10, my modified form is shown with the additional washer valve hereinbefore described. It is obvious that a washer valve may be employed instead of the conical valve, or in addition thereto.

Although I preferably construct my entire stopper of glass, it is apparent that it is only necessary to construct the cup shaped portion of transparent substance.

25 The operation of my device is as follows: When desirable to pour the contents from the bottle, the stopper is unscrewed, and the bottle inverted, whereupon the valve or valves become displaced permitting the contents to pass through the openings b', thence out around the cup portion D. It is apparent that the entire contents can thus be poured out without coming in contact with the ribbon E, but when an attempt is made 30 to refill the bottle the valves become reseated thus closing the neck of the bottle, whereupon the mouth will immediately fill and overflow into the groove d coming in contact with the ribbon E and dissolving the non-transparent substance thereon, whereupon the word "Refilled" or other word will become visible through the mouth of the bottle, as shown in Fig. 2.

What I claim and desire to secure by Letters Patent is:—

1. An indicator of the kind described comprising a ribbon and a non-transparent covering therefor, substantially as and for the purpose described.

50 2. An indicator of the kind described comprising a ribbon and a perishable non-transparent covering therefor, substantially as and for the purpose described.

3. An indicator of the kind described comprising a ribbon and a soluble non-transparent covering therefor, substantially as and for the purpose described.

4. In a bottle of the kind described, the combination with an indicator, of a non-transparent covering therefor and means whereby the inflow of fluid will remove said covering, substantially as described.

5. In a bottle of the kind described, the combination with an indicator, of a perishable non-transparent covering therefor and means

whereby inflowing fluid will be forced into contact with said covering when the bottle is re-filled, substantially as described.

6. In a bottle of the kind described, the combination with an indicator, of a soluble non-transparent covering therefor, means for protecting said covering during the outflow of the contents and means whereby inflowing fluid is forced into contact with said covering of said indicator, substantially as described.

7. In a bottle of the kind described, the combination with an indicator, of a soluble non-transparent covering therefor, a transparent compartment provided with an opening to receive said indicator, said compartment being constructed to protect said indicator from the contents of the bottle when poured out, and means whereby the liquid is forced into contact with the soluble covering of said indicator when the bottle is refilled, substantially as described.

8. In a bottle of the kind described, the combination with an indicator, of a soluble non-transparent covering therefor, a transparent compartment provided with an opening to receive said indicator, said compartment being constructed to protect said indicator from the contents of the bottle when poured out, a valve constructed to permit the outflow of the contents but constructed to prevent refilling, whereby the liquid is forced through said opening in said compartment and into contact with the soluble covering of said indicator, substantially as described.

9. In a bottle of the kind described, the combination with an indicator, of a soluble non-transparent covering therefor, a transparent compartment provided with an opening to receive said indicator, said compartment being constructed to protect said indicator from the contents of the bottle when poured out, means for locking said compartment in the bottle and means whereby the liquid is forced into contact with the soluble covering of said indicator when the bottle is refilled, substantially as described.

10. In a bottle of the kind described, the combination with an indicator, of a soluble non-transparent covering therefor, a transparent cup shaped compartment adapted to hold said indicator, means for locking said compartment in the bottle whereby outlet passages are formed around said compartment, a non-detachable stopper adapted to close the bottle and compartment and to prevent access to said compartment and a valve adapted to permit the outflow of the contents but adapted to prevent the refilling of the bottle, whereby the liquid is forced into said compartment and into contact with the soluble covering of said indicator, substantially as described.

11. In a bottle of the kind described, the

- combination with a disk portion adapted to fit into the mouth of the bottle, said disk being permanently secured thereto and being provided with suitable openings, an upwardly extending cylindrical portion provided at its upper end with a threaded orifice, a transparent cup shape portion secured to said cylindrical portion and forming an annular groove around the same, an indicating device located in said annular groove, a stopper provided with a threaded stem adapted to fit into said threaded orifice in said cylindrical portion, a locking ring on said stem to prevent the stopper from being withdrawn, said stopper being provided with a portion to 15 prevent access to said indicator, a valve adapted to permit the outflow of the contents but closing the neck of the bottle upon refilling same, substantially as described.
